UNITED STATES PATENT OFFICE.

JOSEPH J. MARTY, OF BOSTON, MASSACHUSETTS.

POWER-DRIVEN MECHANISM.

1,261,419.

Specification of Letters Patent.

Patented Apr. 2, 1918.

Application filed November 17, 1916. Serial No. 131,973.

To all whom it may concern:

Be it known that I, JOSEPH J. MARTY, citizen of the United States, of Boston, in the county of Suffolk and State of Massachusetts, have invented certain new and useful Improvements in Power-Driven Mechanism, of which the following is a specification.

My invention relates to guards for machinery which serve to protect the operator or attendant from injury, and the object thereof is to provide an improved guard of this kind particularly adapted to extractors such as are used in laundries to remove water from clothes.

Extractors of the kind referred to comprise a housing having a central opening in its top and containing a revolving basket within which the wet clothes are placed. The basket with its contents is very rapidly rotated so that the water contained in the clothes will be removed and thrown off by centrifugal force. It is common practice for an operator of such a machine to reach down into the basket immediately after starting the machine and before the basket acquires much speed and to push the clothes snugly down into the basket. Sometimes while engaged in this operation a wet garment will become entangled with his hand or arm and also with the rotating shaft which supports the basket with the result that the operator's arm is twisted around the shaft and broken or seriously injured. My invention makes it impossible for an accident of this sort to happen and it consists of a guard for machinery embodying the novel features of construction and mode of operation set forth in the following description and particularly pointed out and defined in the claims at the close thereof.

In the accompanying drawings—

Figure 1 is a side elevation partly in section of a hydro-extractor for laundries constructed in accordance with my invention.

Fig. 2 is a side elevation of a part of the mechanism shown in Fig. 1 but showing the gate, hereinafter described in its open position.

Fig. 3 is a side elevation of the lower portion of the gate by itself.

Fig. 4 is a section on line 4—4 of Fig. 1, drawn to a larger scale.

Fig. 5 is a front elevation partly in section of a portion of the machine showing the gate in its closed position.

In the accompanying drawings I have

shown my invention embodied in a hydro-extractor for use in laundries but, as will be clear later, my invention may be embodied in other kinds of machines.

60

Having reference to the drawings, 1 represents the housing of the extractor and 2 the rotatable basket arranged within said housing. The basket 2 is supported by a shaft 3, Figs. 4 and 5, supported at its upper end by a bearing in an arm 4 projecting from a post 5. Near its upper end the shaft 3 carries a pulley 6 connected by a belt 7 with a pulley 8 fast on the main driving shaft 9. Shaft 9 carries a tight pulley 10 and a loose pulley 11 which coöperate with a driving belt, not shown, that is controlled by a belt shipper 12, mounted in guides 13. To the belt shipper 12 is pivotally connected one end of a control member 14 whose opposite end extends through a slot 15 formed in the frame of the machine and is provided with a handle 16 by means of which the control member 14 is manually manipulated to operate the belt shipper 12, and to shift the driving belt, not shown, back and forth between the tight and loose pulleys 10 and 11. The housing 1 is made with a cap 17 formed with a central opening 18, which is of about the same diameter as the opening in the upper end of the basket 2. The clothes from which the water is to be extracted are dropped into the basket 2 through the central opening 18 and it is customary for the operator to use his hand and arm to force the clothes snugly down into the basket and it is common practice for the operators of machines of this kind to do this immediately after having pulled the control member 14 forward to 70 start the machine. This, as already explained, frequently results in injury to the arm of the operator. In accordance with my invention I provide a movable gate 19 which is adapted to occupy a position in front of the shaft 3 with its ends adjacent the two uprights 20 forming part of the frame of the machine and when in that position said gate makes it impossible for the operator to insert his hand within the machine. This 75 gate 19 is provided near its lower end with three trucks 21 mounted upon a rail 22 secured by screws, or otherwise, to the cap 17 within the central opening 18 thereof. The rail 22 is in the form of a ring and when 80 movement of the gate is not opposed or prevented, as presently to be described, said gate

may be swung around shaft 3 into a position back of the latter so as to render the interior of the basket 2 accessible. In accordance with my invention the gate 19 and the control member 14 are interconnected so that the control member 14 cannot be shifted to start the machine until the gate 19 has been closed, that is, until the gate 19 has been swung into position in front of shaft 3, and so that after 10 the gate has been closed and the machine has been started the gate 19 cannot be opened again until after the control member 14 has been shifted to stop the machine. The means, herein shown for securing this mode 15 of control, comprises a lock bar 23 pivoted at one end at 24 to one of the uprights 20 and having its opposite end made with a fork straddling the cam 25 herein shown as a semi-circular bar having inwardly bent ends 20 secured to the ends of the gate 19 and having its middle portion fastened by means of a screw to a post 27 projecting from gate 19. One end of this cam rod 25 is made with a deflection 28 so that the portion 29 of the cam 25, which is in engagement with lock bar 23, when gate 19 is closed, is higher than the other portion of cam 25.

The lock bar 23 is arranged adjacent the slot 15 through which the control member 30 14 extends and said lock bar extends across the top of the control member and is locked in its uppermost position by the latter, when said control member occupies its forward position with the driving belt on the tight 35 pulley 10. It will thus be seen that with the lock bar 23, thus supported by the control member 14, the gate 19 cannot be swung in the direction of the arrow, Fig. 4 into its open position for the reason that the 40 deflection 28, of cam 25, cannot pass the lock bar 23 because the latter is held by the control member 14 against being swung downward.

The control member 14 is made upon its 45 underside with a notch 30, positioned so that when the control member 14 is shoved rearwardly into position to carry the driving belt onto the loose pulley, 11, said notch registers with the lower end of the slot 15 and permits the forward end of the control 50 member 14 to swing downward thereby leaving the lock bar 23 free to swing downward under the influence of deflection 28 when the gate 19 is swung toward the right, Fig. 5. When the gate 19 is swung to the rear 55 of shaft 3, into its open position, the downward movement of the lock bar 23, occasioned by the deflection 28, brings the lock bar into position close to the top of control 60 member 14 so that it serves to lock the control member against being lifted to disengage the notch 30 from the lower end of slot 15 and, as will be clear, said control member is thus held immovable until the gate 65 19 is swung back to its closed position again.

When the gate 19 has been swung back to its closed position again, the deflection 28 lifts the lock bar 23 into its uppermost position again so that thereafter the forward end of the control member 14 can be lifted sufficiently to disengage notch 30 from the lower end of slot 15 and pulled forward to start the machine.

The gate 19 comprises a frame made up of two horizontal semi-circular bars 31 and 32 connected by three upright bars 33, the lower ends of the latter extending below the trucks 21 and formed into hooks 34, 35 and 36, projecting under the rail 22 which prevent upward displacement of the gate when 75 deflection 28 strikes lock bar 23 or when the operator attempts to shift the control member 14 to start the machine while the gate 19 occupies its open position. A lattice of 80 interwoven wire rods 37, secured to the 85 frame of the gate, completes the latter.

In order to prevent the gate 19 from being rotated in the wrong direction when shifting it from its closed to its open position, and in order to limit its movement to 90 one-half of a revolution around the shaft 3, a stop 38 is provided. This stop is a small plate secured to the under side of the rail 22, so that when the gate is swung from its 95 open to its closed position, the hook 34 engages said stop and limits its movement in that direction and when swung from its closed to its open position the hook 36 engages said stop and limits its movement in that direction.

It is customary to provide machines of the kind herein illustrated, with a sheet metal guard 39 secured to the uprights 20 of the machine, said guard surrounding the rear half of the opening 18. Thus when the 105 gate 19 occupies its closed position it is impossible for the operator to insert his arm into the opening 18 from any direction.

My improved guard is simple in construction and mode of operation and effectively protects the operator from injury through the cause above referred to and also makes it impossible for anyone to insert his hand or arm into the machine while it is in operation.

The cam rod 25 is at a convenient height, and in a convenient position, to be used as a handle by means of which to rotate the guard 19 when opening or closing the same.

Pivoted at 40 to one of the uprights 20 120 is a lever 41 whose lower arm is made with a hook 42 coöperating with lock bar 23 and adapted to occupy a position immediately below said lock bar when the latter is held in its uppermost position by cam bar 25. 125 The upper end of lever 41 is connected through a pin and slot joint 43 with an arm 44 fast on a rock shaft 45 journaled in a bracket 46 secured to the frame of the machine. This shaft 45 also has fastened to 130

it a bell crank lever 47, one arm of which carries a stud 48 engaging a grooved collar 58 fixed on a spindle 49 supported near its front end by a bracket 50 on the frame, said 5 front end also carrying a hand wheel 51. The rear end of spindle 49 is threaded and occupies a threaded socket provided within a yoke 52 that is pivoted at 53 to a brake lever 54. The brake lever 54 is pivotally 10 supported and carries a brake shoe 55 co-operating with the periphery of pulley 6. Mounted on the spindle 49 is a compressed coiled spring 57, one end of which bears against bracket 50 and the other end against collar 58 so that when spindle 49 is manually 15 rotated in one direction, its inner threaded end, acting through socket 52, swings brake lever 54 toward and against pulley 6 but with a yielding pressure supplied by spring 57. That is, after brake lever 54 has been brought into engagement with pulley 6, continued rotation of spindle 49 moves the latter endwise in bracket 50 against the pressure of spring 57. It 20 will thus be clear that when spindle 49 is rotated to set the brake, the latter is first set and thereafter an endwise movement is imparted to spindle 49 which acts through collar 58, bell crank 47, rock shaft 45 and arm 44 to swing lever 41 in a direction to remove hook 42 from beneath lock bar 23 so that gate 19 can only be opened after and while the brake is applied to pulley 6. This 25 makes it impossible to open gate 19 while the shaft 3 is in motion. The arm 60 of bell crank 47 serves as an indicator to show the position of the brake.

What I claim is:—

1. In a hydro-extractor, the combination 40 with a housing provided with an opening through which the articles to be treated are inserted and removed, of a rotatable basket within said housing, a guard mounted on said housing for movement about the axis of rotation of said basket to open and close said opening, a driving shaft connected to said basket, driving means for said shaft, a power-controlling member to connect said driving means to and disconnect it from the 45 shaft, and an interlocking connection between said guard and said power-controlling member whereby the controlling member is locked from movement except when the guard is closed and the guard is locked 50 closed so long as the controlling member is in position to connect the driving means to the driving shaft.

2. In a power-driven machine, the combination 55 with a driving shaft, of driving means therefor, a power-controlling member to connect said driving means to and disconnect it from said shaft, a device operated by said shaft, a guard for said device, a 60 brake for said device, and an interlocking connection between said guard and brake

whereby when the guard is closed it is locked from movement so long as the brake is in inoperative position, but is unlocked when the brake is applied.

3. In a hydro-extractor, the combination 70 with a housing, of a rotatable basket within said housing, said housing having an opening, a guard mounted on said housing and movable about the axis of rotation of the basket to open and close said opening, drying means for said basket, a power-controlling member movable to render the driving means operative or inoperative to rotate the basket, and a locking member which is rendered operative by the controlling member 80 when the latter is in position to establish operative driving connections between the driving means and the basket to lock the guard in closed position and which when the controlling member is in position to render 85 the driving means inoperative is rendered operative by the opening movement of the guard to lock the controlling member from movement.

4. In a hydro-extractor, in combination, a 90 housing provided with an opening through which the articles to be treated are inserted and removed; a rotatable basket within said housing; a guard movably mounted on said housing adjacent said opening so as to occupy open or closed positions; a power controlling member; and means interlocking said guard and member through which each controls the other so that the guard can be 95 opened only when the member is shifted into 100 position to throw the power off and said member can be shifted to throw the power on only after said guard has been closed.

5. In a hydro-extractor, in combination, a 105 housing provided with an opening through which the articles to be treated are inserted and withdrawn; a rotatable basket within said housing; an annular rail on said housing and surrounding said opening; a guard movably mounted on said rail so that it can 110 be shifted thereon into and out of closed position; a power controlling member, and means interlocking said guard and member so that the guard can be opened only when said member is in position to disconnect the 115 machine from the power and so that said member can be shifted to connect the machine with the power only when the guard occupies its closed position.

6. In a hydro-extractor, in combination, a 120 housing provided with an opening through which the articles to be treated are inserted and removed; a rotatable basket within said housing; an annular rail surrounding said opening; a guard for said opening provided 125 with trucks mounted on said rail so that the guard is movable on the latter into open or closed position; a power controlling member, and means interlocking said guard and member so that the guard can be opened only 130

when the said member is in position to disconnect the machine from the power and so that said member can be shifted to connect the machine with the power only when said guard occupies its closed position.

7. In a hydro-extractor, in combination, a housing made with an opening through which the articles to be treated are inserted and removed; a rotatable basket within said housing; an annular rail surrounding said opening; a guard gate movably mounted on said rail so that it can be shifted into and out of closed position; a stop for limiting the movement of said guard gate on the rail; a power controlling member, and means interlocking said guard gate and member so that the guard gate can be opened only when said member is in position to disconnect the machine from the power and so that the said member can be shifted to connect the machine with the power only when the guard gate occupies its closed position.

8. In a hydro-extractor, in combination, a housing having an opening, a rotatable basket therein, a guard mounted on the housing for movement about the axis of rotation of the basket thereby to open and close said opening, driving means for the basket, a shiftable power-controlling member, and means through which the guard is locked in its closed position by the movement of said power-controlling member when it is shifted to throw the power on while after it is shifted to throw the power off the opening movement of the guard will lock the power-controlling member from movement.

9. In a power driven machine, in combination, a device to be operated, driving means

therefor, a power-controlling member for connecting said driving means to or disconnecting it from said device, a movably-supported guard, a brake, means to operate it, locking means controlled by the shifting movement of said power-controlling member into position to throw the power on to lock the guard closed and by the opening movement of said guard to lock the power-controlling member in a position to disengage the driving means from said device, and means controlled by the brake-actuating means to lock the locking means when the brake is free and to release said locking means when the brake is set.

10. In a power-driven machine, the combination with a driving shaft, of driving means therefor, a power-controlling member to connect the driving means to and disconnect it from the driving shaft, a device operated by said shaft, a guard for said device, a brake for said device, and an interlocking connection between said guard, brake and power-controlling member whereby when the guard is closed it will be locked from movement until the controlling member is shifted to disconnect the driving pulley from the driving shaft and the brake is applied, and when the guard is open it locks the controlling member from movement into position to connect the driving pulley to the driving shaft.

In testimony whereof I have affixed my signature, in presence of a witness.

JOSEPH J. MARTY.

Witness:

GEORGE F. MOULTON.
